(57) CLAIM

The ornamental design for a pedicure spa base, as shown and described.

DESCRIPTION

FIG. 1 is a prospective front-side view of the pedicure spa base.

FIG. 2 is a perspective rear-side view of the pedicure spa base.

FIG. 3 is a left-side view of the pedicure spa base.

FIG. 4 is a right-side view of the pedicure spa base.

FIG. 5 is a top view of the pedicure spa base.

FIG. 6 is a front view of the pedicure spa base.

FIG. 7 is a rear view of the pedicure spa base; and,

FIG. 8 is a prospective top view of the pedicure spa base showing one location of the spa chair and spa basin. The broken lines in the drawings are for illustrative purposes only and form no part of the claimed design.
